ABSTRACT

Method for automatic cop doffing in a ring spinner. According to the method, it is provided to grip the reels or cops by pliers carried by a spinner doffing device, adjacent the bottom end thereof to clamp the last coils of wound up yarn; to lift the reels or cops by a distance sufficient to tear the yarn and place a reel again on its associated spindle; then to grip the reels or cops at a higher location than the former, lifting such reels or cops to be unthreaded from the spindles and to complete the doffing operations for replacement with spools.

FIG. 3

FIG. 4

METHOD FOR AUTOMATICALLY DOFFING COPS IN A RING SPINNER

This invention generally relates to ring spinners, and more particularly to a method for automatically doffing cops and replacing the cops with new spools.

From a previous patent to the same assignee of this patent application, an automatic spinner is known as provided with a device for automatically doffing cops, the device substantially comprising a movable pliers-carrying bar located on one side of the spinner at the spindle-carrying frame, which pliers-carrying bar is provided with a plurality of pliers suitable to grip the cops and spools. Said pliers-carrying bar is movable vertically and horizontally supported between a lower position thereof underlying the spindle-carrying frame and an upper position thereof overlying said frame through an articulated framework carried by structure horizontally slidable along suitable guide means, said framework and supporting structure being driven to provide for lifting and lowering the pliers-carrying bar and transversing thereof, as above stated.

In accordance with the apparatus as proposed in the above mentioned patent, and according to its operation as provided therein, after forming a thread supply on each of the spindles prior to stoppage thereof, under the yarn winding spool, and after the ring and yarn guiding loop overturning, the spindle gripping pliers would clamp each cop at the top end of the cylindrical portion for doffing from the spindle and depositing on a corresponding pin of a continuous conveyor underlying the frame and providing for removing the cops and supplying the new spools which, when placed on the spindles previously cleared off, would serve to wind up a further cop.

However, the method as used with the device according to the previous patent can be conveniently used where cotton and/or low stretch yarns are concerned. In case of wool, or synthetic, or long fiber and generally high stretch and tensile stress yarns, upon the yarn break there would occur disadvantages that can be overcome by the doffing method according to the present invention.

According to the method as provided for by the apparatus disclosed in the previous patent, each of the pliers would clamp the corresponding cop at a top position such that the last yarn coils wound on the cop periphery between the pliers and the supply formed at a suitable location on the spindle have an undue extension and such that at doffing, where the yarn should be highly resistant and have a high stretch, said coils can wind up, stretch and finally break, leaving a yarn tail of such a length to interfere at the next spinning resumption step with the thread length supplied by the spinner to be wound up on the new spool.

Where highly resistant or high stretch yarns are concerned, this disadvantage may occur on a very high percentage of spindles (spinners having up to 500 spindles and more are available), so that a loss of time would result for the need of employing special operator teams for joining the broken threads together, which loss of time can often become unacceptable for a regular economical operation of the spinner.

This disadvantage is overcome by the cop doffing method according to the present invention, which method provides to reduce the extension for the coil or coils between the cop clamping pliers and the yarn sup-

ply formed on the spindle, so as to provide a minimum yarn stretch, also making it impossible for the coils to unthread from the cop. In this case, the yarn break at any location in the length between the pliers and supply will always leave a short yarn tail, such as not to interfere with the new thread being supplied at the time of spinning resumption.

Particularly, the method for automatically doffing the cops in such a spinner having a plurality of pliers for gripping the cops and yarn winding spools, said pliers being mounted to a pliers-carrying rod or bar laterally of the spinner and movably vertically and horizontally supported between a bottom position thereof at a conveyor belt for feeding the spools and unloading the cops and at least one position at the top of the spindle-carrying frame for said yarn, comprise the steps of moving the pliers in said pliers-carrying bar to a top position thereof; to grip the cops at a location corresponding to or adjacent the lower end of the associated spool; to close the pliers to grip the cops by firmly pressing the last coil or coils of wound up yarn; to lift the cops by a distance sufficient to tear the yarn in the length between the cop gripping location and a yarn supply previously wound up on the spindle beneath the spool; and finally to doff the cops from the spindles, replacing the same with spools for the next spinning resumption.

Although in the specific embodiment hereinafter disclosed for an apparatus suitable to practice in the present method, the pliers are of a pneumatic character and carried by pairs to separately grip one cop and one spool, respectively, it should be understood that such pneumatic pliers could be as well replaced with pliers of any other type, such as mechanical pliers, without any change to the novel principle of the present method that can by anyhow practiced. Additionally, in some presently used spinners over the frame the available room is insufficient for doffing a cop, gripping it by the pliers at its bottom end. Therefore, an intermediate step is provided where the cop, following the yarn break, is placed again on the spindle, the pliers are loosened and upward moved by a predetermined length to grip the cop at a higher location prior to doffing said cop.

These and further features of the method according to the present invention will be more particularly hereinafter explained in the following description in connection with the figures of the accompanying drawings showing an automatic spinner provided with an apparatus for automatic cop doffing, and in which:

FIG. 1 is a schematic cross-sectional view of a spinner having an automatic cop apparatus adapted to carry out the method according to the invention;

FIG. 2 is a schematic fragmentary side view of the spinner shown in FIG. 1; and

FIGS. 3 and 4 are enlarged views showing two subsequent steps in doffing a cop as provided by the method according to the invention.

Referring to FIGS. 1 and 2, a short description will now be given of the construction of the doffing device suitable to carry out the method according to the invention, as said device is not an essential part of the invention, but replaceable by any other type of devices.

As it will be seen in FIGS. 1 and 2, wherein a spinner 10 has been diagrammatically shown omitting to show those parts of the spinner not essential for fully understanding the invention, it will be seen that said spinner

10 has on two opposing sides spindle-carrying frames 11 cantilever projecting and supporting a plurality of spindles 12 suitably rotatably driven through the belts in a per se well known manner.

For each of the spinner spindle-carrying frames 11 the use is contemplated of a device for cop doffing, which, as shown, is subsequently formed of an articulated framework comprising a horizontal bar 13 supporting a plurality of pairs of pliers 14, 15 inwardly facing, of which the external pliers 15 are for gripping the yarn cops 16 on the spinner spindles 12, and the internal pliers 14 are for gripping the spools 17 carried by corresponding pins 18 of a continuous conveyor 19 at a bottom position underlying said frame 11. Obviously, said continuous conveyor is controlled to carry the individual spools 17 to a position in alignment with the gripping pliers.

The pliers-carrying bar 13 is supported for vertically moving between at least one top position at the spindles 12, as shown on the right-hand side of FIG. 1, and a bottom position underlying the frame 11 at said conveyor, as shown on the left-hand side of FIG. 1, by means of an articulated framework, in addition to said bar 13 comprising, in the embodiment shown in FIG. 1, two side rods pivoted at one end thereof to the pliers-carrying bar 13, and at the other end thereof to a corresponding block 23 sliding along suitable horizontal guide means carried by a structure 24 horizontally movable from an inner position underlying the spindle-carrying frame to a second position externally of the spinner by a sufficient distance to avoid any interference of the pliers-carrying bar 13 with said frame 11 or other projecting parts of the spinner, as the latter is upward and downward moved. The two sliding blocks 23 are connected to the two opposing runs of a chain 23' to control the movement thereof in the opposite directions along said guide means.

This articulated framework supporting structure 24 is driven from horizontal movement on suitable guide means by a rack system 25, diagrammatically shown in FIG. 1, which through a pinion 26 is operated to move by any drive system under the control of a driving shaft for the spinner, or a suitable motor (not shown).

In the exemplary embodiment shown, the pliers 14 and 15 for gripping the spools 17 and cops 16, respectively, are pneumatic pliers comprising inflatable tubular sleeves clamping the spool and cop, respectively, throughout the diameter thereof. However, if desired, said pneumatic pliers could be replaced by mechanical pliers or the like, without any change in the principle on which the method according to the present invention is grounded.

The spinner 10 is also provided with members for feeding and guiding a yarn 27, which is to be wound up on the reels 16, such as loops 28 and guide rings 29 that can be overturned in per se known manner.

The operation will now be described for said doffing device, in accordance with the general principles of the present method, by considering an intermediate step contemplating to grip again the cops after thread break for doffing in spinners having a reduced free room in height. However, it is to be understood that for spinners of other designs this intermediate step could be also omitted.

Prior to stopping and when the reels 16 are fully filled, the spindles will build up at a location underlying the reel a thread supply 30, as clearly shown in FIGS.

3 and 4 of the accompanying drawings, by winding up two or more yarn coils. Then, said loops 28 and rings 29 are overturned in per se known manner for starting the doffing steps.

- 5 Then, the doffing device supporting the pliers-carrying bar 13 is operated and first through an outward horizontal movement then through an upward vertical movement and an inward horizontal movement carries said bar 13 to a top position where said pliers 15 are overlying and aligned with the reels 16. Then, by a subsequent downward vertical movement of said bar 13, the pliers 15 are carried to a position, shown by solid lines on the right-hand side of FIG. 1 and in FIG. 3, where said pliers 15 are at or adjacent the bottom end of the associated reels 16 or spools.

Once at this position, the pliers will inflate, where pneumatic pliers are concerned, and generally clamp the reels at said bottom position. Hereinafter the description will proceed for the several doffing steps, reference being had to the pneumatic type of pliers, the operation with pliers of other design being apparent.

After the pliers have gripped the reels 16 at the bottom end thereof and at the last coil or coils of the wound up yarn, as clearly shown in FIG. 3, said articulated framework will cause the pliers-carrying bar 13 to partially lift by a distance sufficient to tear the thread in the length between the clamping location for the pliers on the reel and said yarn supply 30.

As clearly shown in FIG. 4, by gripping the reel 16 adjacent its bottom end, a reduction is provided in the free thread length along which a break can occur, whereby even though subjected to some stretch as the thread is torn, there is formed at the thread supply 30 a short thread 'tail' 31 (FIG. 4), having the length of a fraction of coil, or at the most one yarn coil. Also the maximum length for said thread tail 31 is such that said tail is left at a free condition without interfering with the thread 27 being supplied by the spinner upon spinning resumption. Should the thread tail 31 be longer, as where each of the pliers 15 would clamp the reel 16 at a top position, said thread tail 31 would entangle or interfere with the thread 27, thereby hindering the winding up thereof on the spool, as shown by dashed lines in FIG. 4.

By clamping the reel 16 at its bottom end and at the last coils of wound up yarn, in addition to reducing the stretch of the thread tail 31 when breaking, the thread length subjectable to unthreading from the reel or cop is also made very short. Thus, a ready and reliable yarn break is provided during doffing operations.

That the thread tail 31 does not interfere with the yarn 27 upon spinning resumption is also because the ring-carrying carriage will move upwards, prior to winding, by a distance of at least 4-5 cm. from the location where said supply 30 is formed, and this in a well known manner.

After the pliers-carrying bar 13 is lifted for a distance sufficient to cause a thread break, as above stated, the upward movement can be continued to completely unthread the reel 16 from the spindle 12, where a sufficient height space is available in the spinner, then laterally moving and subsequently lowering down again to grip the new spools and place the cops 16 on the pins of the conveyor that have been previously cleared. Otherwise, should enough space be not available above the spindles, the pliers-carrying bar 13, carried by said articulated framework, would lower down again to the

position shown in FIG. 3, mounting again the reels 16 on the associated spindles.

Then the pliers 15 will release the reels or cops and by a further upward movement of the pliers-carrying bar 13, said pliers are moved to an intermediate or top position to grip the reels at a higher location than the former, as schematically shown by dashed lines on the right-hand side of FIG. 1.

The pliers-carrying bar is then lifted until the bottom of each spool is at a higher level than the associated spindle; the articulated framework assembly is outwardly moved and finally caused to re-enter over the conveyor belt until the axis of each pliers 14 for the spools is coincident with the axis of the spools 17 carried by the corresponding pins 18 of said conveyor. The bar 13 further moves downward by a short distance until the pliers are at about two thirds of the level of the associated spools. The pliers 15 inflate gripping the spools and the system repeats the opposite movements to bring the spools over the spindles, threading such spools thereon. During these movements, the pliers 15 always hold the associated cops or reels at a gripped condition.

Once the pliers have been loosened and have released the spools on the spindles, the pliers are moved away from the spools and the pliers-carrying bar 13 is again moved back to its bottom position underlying the frame 11 to carry the cops on the conveyor belt 19, which is then operated to feed and unload said cops into a proper container at one end of the spinner. At this time, the spinning and winding up operations for the yarn 27 on the spools has already been resumed.

It should be understood that the foregoing, as referred to a doffing apparatus according to the specific embodiment shown in the accompanying drawings, is not to be intended as a limitation, since the sequence of the doffing steps could be other than that herein disclosed where allowable by the spinner structure and where the position for the reel or cop pliers and for the spool pliers should be reversed or different from that shown. However, in any case the statement should be unaltered to grip the reels 16 by the associated pliers at the bottom end of the reel, or at the closest location as possible to the bottom end of the spool in order to reduce the thread length along which a break might occur, thereby reducing the length of the thread "tail" remaining attached to the supply normally wound up on the spindle, as previously stated.

What is claimed is:

1. A method for automatic cop doffing in a spinner having a plurality of pliers for gripping the reels or cops

and the yarn winding up spools, said pliers being carried by a plier-carrying bar, vertically and horizontally movable supported between one bottom position thereof adjacent a conveyor belt for feeding the spools and unloading the cops, and at least one top position relative to the spindle-carrying frame of said spinner, wherein a provision is made for moving said pliers-carrying bar to a top position with said pliers arranged at a closest location as possible to the bottom end of said cops; clamping the pliers by gripping the cops at the bottom end thereof firmly pressing the last coils of wound up yarn; lifting the cops by a distance sufficient to tear the thread within the length between the gripping location for one pliers on the cop and a thread supply previously wound up on the spindle underlying the spool; and finally doffing the cop from the spindle and replacing it with a spool.

2. A method for automatic cop doffing in a spinner as claimed in claim 1, wherein following the thread break step, it is further provided to again lower the cop, threading it on the associated spindle, to loosen the pliers grip lifting it by an upward movement of the pliers-carrying bar; to grip the cop at a location overlying the former, and then unthread the cop from the spindle for carrying out the subsequent doffing operations, replacing the cops with the spools.

3. A method as claimed in claim 1, wherein use is made of a pneumatic type of pliers.

4. A method as claimed in claim 1, wherein use is made of a mechanical type of pliers.

5. A method as claimed in claim 2, wherein following the yarn break of each cop carried by a pliers of the movable bar, it is provided to lower the pliers-carrying bar to thread again the cops on the associated spindles by gripping the same at an overlying location, further comprising the steps of unthreading the cops from the spindles by a further lifting movement of the pliers-carrying bar, outwardly laterally moving it and then lowering it to its bottom position with the pliers for the spools in alignment therewith, clamping said spools carried by said conveyor, and the moving said pliers-carrying bar in opposite direction to the first direction by a composite movement for the articulated framework of its supporting structure to carry the spools upward as available on the spinner spindles, and lower down again said pliers-carrying bar still holding the cops to arrange the latter on said conveyor; the cops being then carried to an end unloading position of the spinner.
